FEEDING MECHANISM FOR STRING-BEAN CUTTERS, &c.

1,095,228.

Specification of Letters Patent.

Patented May 5, 1914.

Application filed June 19, 1908. Serial No. 439,360.

To all whom it may concern:

Be it known that we, WILLIAM B. PHINNEY, a citizen of the United States, and resident of Westfield, in the county of Chautauqua and State of New York, and ROGER C. ADAMS, a citizen of the United States, and resident of Buffalo, in the county of Erie and State of New York, have invented a new and useful Improvement in Feeding 10 Mechanism for String-Bean Cutters, &c., of which the following is a specification.

This invention relates to a feeding mechanism which is more particularly designed for feeding string beans to a machine which is adapted to cut off or trim opposite ends of the beans preparatory to cooking or canning the same although the machine may also be used for feeding other articles of the same general shape to a machine which is intended to operate upon such articles.

Owing to the irregular length, thickness and shape of string beans it has been found difficult to feed the same uniformly to the machine which cuts or trims the ends thereof.

The object of this invention is to produce means whereby the feeding of string beans and like articles to another machine is effected expeditiously and with maximum regularity and reliability.

In the accompanying drawings consisting of 3 sheets: Figure 1 is a side elevation of our improved feeding device showing the same organized for feeding string beans to a machine which is adapted to cut off opposite ends of the beans. Fig. 2 is a vertical longitudinal section of the same. Fig. 3 is a top plan view thereof. Fig. 4 is a fragmentary vertical transverse section in line 4—4, Fig. 2. Fig. 5 is a fragmentary horizontal section in line 5—5, Fig. 2.

Similar letters of reference indicate corresponding parts throughout the several views.

For the purpose of illustrating the use of this improved feeding mechanism the same is represented in the drawings as associated with the carrying mechanism of a string bean cutter or trimmer which operates to cut off opposite ends of string beans. That portion of this carrying mechanism which is shown in the drawings comprises an endless chain belt A having an upper horizontal operative portion and a lower inoperative portion, a sprocket wheel a around which passes

the receiving end of the carrying belt, a shaft 55 B carrying said sprocket wheel and journaled in bearings on a reciprocating support C and a plurality of pockets or buckets C¹ arranged side by side on the belt and extending with their length transversely to the 60 line of movement of the carrying belt. The improved feeding device is intended to deliver string beans successively into these pockets so that they are arranged therein transversely to the line of movement of the 65 pockets. After the beans have been thus deposited in these pockets the latter carry the same forwardly to the cutters which cut off opposite ends of the same. A machine for thus cutting or trimming off the ends of the 70 beans is shown in the pending application filed November 16th, 1907 and numbered 402,487.

The improved feeding device may be variously constructed and still embody the 75 essence of this invention but the organization shown in the drawings is preferred and is constructed as follows: D, D represent two longitudinal side walls which are supported at their rear ends on the floor while 80 their front ends overhang the rear or receiving parts of the carrying mechanism of the bean cutter. Arranged across the space between the rear ends of these side walls is a forwardly inclined bottom E which together 85 with said side walls forms a hopper which is closed at the sides and bottom and is open at its upper or rear inlet end and also open at its front or outlet end. Into this hopper the beans to be cut or trimmed are deposited 90 promiscuously and the latter are carried out of this hopper, a few at a time, by means of an elevator which moves past the hopper outlet and lifts the beans successively therefrom. The preferred form of elevator for 95 this purpose which is shown in the drawings comprises an endless belt F having a forwardly inclined receiving portion f which moves upwardly past the outlet of the hopper, a delivery portion f¹ which inclines forwardly at a lesser angle than said receiving portion and a rearwardly inclined return portion f² extending from the front end of the delivery portion to the lower end of the receiving portion. This elevator belt passes 100 at its lower end around a roller or pulley G which is journaled on the side walls below the hopper and at its upper end around a

- roller or pulley G^1 which is mounted on a transverse shaft g journaled on the side walls above the rear end of the carrying mechanism for the bean cutter while the operative portion of the belt between its receiving and delivery portions is supported by an intermediate pulley or roller G^2 which is journaled on the side walls and produces the rearward and upward deflection in this 5 part of the elevator belt whereby the receiving and delivery parts of the same are caused to stand at an angle relatively to each other. On its outer side the elevator belt is provided with a plurality of buckets, wings or pockets 10 h which are preferably constructed by means of forwardly inclined cleats or strips secured equidistant to the outer side or face of the elevator belt.
- As the operative portion of the elevator 15 belt passes the outlet of the hopper each of its buckets picks up some of the beans therein and carries the same upwardly. In order to produce a practically tight joint between the lower edge of the hopper outlet 20 and the elevator and prevent the beans from escaping at this point a yielding shutter or flap is provided which preferably consists of a sheet of flexible material H which is secured at its rear end to the hopper bottom 25 to mat at the lower edge of its outlet while its rear end engages with the rear or operative side of the elevator. As the buckets of the elevator belt pass the shutter the latter is deflected sufficiently to permit the buckets to 30 pass and after the buckets clear the shutter the latter again springs forwardly into engagement with the elevator belt, thereby producing a packing or yielding closure or joint between the hopper and the elevator.
- It has been found by experience that it is 35 undesirable to overload the buckets with beans inasmuch as this is liable to interfere with their proper presentation to the mechanism which delivers the beans to the cutter. Distributing means are therefore 40 provided for removing the surplus or excess beans from each of the buckets and permitting only a few of the beans or as many as can be properly carried by the same to remain 45 within the buckets and be carried away from the hopper to the carrying mechanism of the cutter. The preferred means for this purpose which are shown in the drawings consist of an endless distributing 50 belt I preferably of the chain type and having its operative portion inclined rearwardly and movable downwardly in a direction lengthwise adjacent to the receiving portion of the elevator belt, sprocket wheels i, i^1 supporting the upper and lower ends 55 of this belt and journaled on the side walls and a plurality of brushes J arranged at intervals on the outer side of the distributing belt. The operative portion of the distributing belt and the receiving portion of the 60

elevator belt preferably diverge downwardly, as shown in Fig. 2, and the length of the bristles of the brushes J is preferably such that each of these brushes in passing the receiving portion of the elevator during its downward movement reaches deeply into the first bucket of the elevator which it meets, then reaches less deeply into the next elevator bucket and then engages only with the outer edge of the next following bucket 70 of the elevator which it meets in its downward course. By this means each distributing brush operates to remove any excess or surplus amount of beans from each bucket which the same may have picked up from the hopper and reduces the liability of improper presentation of the beans to the cutting mechanism. Any beans which are removed from one bucket are brushed downwardly and directed by the brush in advance of the same into the next following bucket of the elevator, so that if any bucket should fail to pick up any beans or picks up a deficient amount of the same, the deficiency will be made up from the excess 80 beans which are removed from other buckets. This distribution of the beans produces uniformity in the feeding operation and insures proper cutting of the same.

Means are provided for causing the brushes J to travel more or less closely to the buckets h and thereby increase or decrease the rate at which beans are being fed to the cutter mechanism as may be found necessary and also to permit of taking up the wear 90 on the brushes. The means for this purpose shown in the drawings consists in mounting the shafts i^2, i^3 of the upper and lower sprocket wheels i, i^1 in bearings i^4, i^5 which are movable at right angles to the receiving portion of the elevator belt and guided in ways i^6, i^7 on the side walls, and adjusting screws i^8, i^9 operatively connected with the bearings i^4, i^5 . By turning the screws i^8, i^9 in one direction or another, the brushes on 100 the operative side of the distributor belt are caused to remove more or less beans from the buckets h and thus regulate the supply to the cutter mechanism.

At the upper front end of the elevator the 115 beans are discharged from the buckets thereof and received by a depositor or lowering device which carries the beans downwardly and delivers the same successively into the several pockets of the feed mechanism of 120 the bean cutter. Although this depositing device may be variously constructed, we prefer the form which is shown in the drawings and which is constructed as follows: K represents an endless depositing or lowering 125 belt having a rear operative portion which inclines rearwardly and which is arranged parallel with and adjacent to the upper end of the return portion of the elevator belt and moves in the same direction as the lat- 130

ter. The upper front part of the depositing belt passes around an upper pulley k which is arranged in front of the delivery roller of the elevator, while its lower rear end 5 passes around a roller or pulley k^1 which is arranged close to the path of the pockets of the cutter mechanism at the receiving end of the same. On its outer side or face the depositing belt is provided at intervals with 10 transverse buckets, wings or pockets l which are adapted to successively receive the beans which are discharged from the delivery end of the elevator and retain them in such a position that their length extends trans- 15 versely to the direction of movement of the depositing belt.

The inner side of each bucket l of the depositing belt is preferably concave in cross section so that it converges from its opposite 20 longitudinal edges toward its bottom, as shown in Fig. 2. This causes any beans which are deposited in an oblique position in the buckets l to be turned by engagement of their ends with the curved walls of the buckets until then arranged parallel with the 25 longitudinal walls of the buckets and at right angles to the direction of movement of the depositing belt. Owing to this formation of the depositor buckets the liability 30 of improper presentation of the beans to the cutter mechanism is materially reduced.

The lower roller of the depositing belt is comparatively small, so that the buckets of this belt make a comparatively quick turn 35 in passing around the underside of this roller from the operative part to the inoperative part of the depositing belt and the path of these buckets as they move around this delivery roller is so close to the carrying 40 pockets of the cutter mechanism that the beans contained in the depositing buckets are delivered into said pockets without dropping them to any considerable extent, thereby reducing the liability of delivering the 45 beans into said pockets other than in a position in which they extend lengthwise in said pockets and transversely to the direction of movement thereof.

In the absence of any provision to prevent it, a crooked or other bean under unusual conditions would be liable at times to escape from the buckets of the depositing belt and drop between the pockets of the cutter feed mechanism in rear of the depositing device at which place the cutter 50 pockets pass around the sprocket wheel a and are temporarily separated, thereby causing the beans to be crushed and clogging the machine. To avoid this, a deflector is 55 provided which intercepts such escaping beans and directs them forwardly to the place where the pockets of the cutter feed mechanism again abut against each other and thereby insures return of such beans 60 into one or another of said cutter pockets.

The preferred deflector for this purpose which is shown in the drawings consists of a curved plate M arranged concentrically relatively to the path of the buckets l as they pass around the delivery roller k^1 and arranged with its upper rear end in rear of said roller while its lower front end is arranged below said roller and close to the upper edge of the cutter mechanism pockets and brush m having its stock or bar arranged in rear of the upper edge of the plate M while its bristles project rearwardly from the stock into engagement with the returning side of the elevator belt and the buckets thereof. By this means a yielding joint is 70 formed between the deflector and the elevator belt which effectually prevents the passage of any beans beyond the operative rear end of the cutter feed mechanism and causes any beans escaping from the depositor to be directed in the pockets of the cutter mechanism. 75

At times a bean is apt to be delivered on the upper edges of the cutter pockets at an oblique angle to the direction of movement 90 of said pockets. Such beans are engaged by and swept off from the upper edges of the cutter pockets by means of a stationary transverse clearing brush n the bristles of which engage with the upper edges of the 95 pockets and which has its stock secured to the side walls D , D or other support.

If a bean should rest upon the upper edges of the cutter pockets in a position lengthwise of the direction of movement of these 100 pockets, the same would be liable to pass the clearing brush n and not be affected thereby. In order to insure the removal of such beans from the upper edges of the pockets and delivery of the same lengthwise 105 into the cutter pockets, a rotatable clearing brush O is provided the same being arranged transversely and horizontally above the path of the cutter pockets in front of the stationary clearing brush and turned in 110 such a direction that the bristles on the underside of the same move rearwardly or in a direction opposite to that in which the operative cutter pockets move. The bristles of the rotary clearing brush engage with the 115 upper edges of the pockets and are arranged to form a spiral or screw shaped conveyer, the several threads or windings of which are separated by intervening spiral spaces similar to a screw conveyer. These spirally arranged bristles of the rotary clearing brush upon engaging the front end of a bean lying on the edges of the cutter pockets in a direction lengthwise of the movement of the same will cause this bean to be pushed laterally and eventually fall into said pockets 120 so as to assume a position therein transversely to the line of movement of the pockets.

In addition to serving as a means for 130

clearing the tops of the pockets of misplaced beans which are arranged at an oblique angle thereon, the stationary clearing brush also operates as a stop or abutment which 5 intercepts and limits the rearward movement of any beans thrown in that direction by the action of the rotary brush.

To prevent any beans from escaping laterally at the sides of the pockets, guard devices P, P are provided which are arranged lengthwise above the ends of the cutter pockets. Each of these guards is preferably constructed in the form of a brush having an upper stock which is secured to the adjacent 10 side wall while its bristles project downwardly into engagement with the adjacent end portions of the cutter pockets, as shown in Figs. 1, 2 and 4.

The relative arrangement of the cutter 20 mechanism pockets, the elevator buckets and the depositor buckets and the timing of these parts is preferably such that each of the depositor buckets receives the charge of beans from one of the elevator buckets, and delivers the same into one of the pockets of the cutter mechanism, thereby insuring uniformity in the feeding of the material to the cutting mechanism.

Any suitable means may be employed for 30 driving the various parts of the feed mechanism, the means for this purpose shown in the drawings consisting of a horizontal driving shaft Q, a belt q passing around pulleys r, r¹ on the driving shaft and the shaft of 35 the delivery pulley G¹ of the elevator, and a chain belt S passing around sprocket wheels t, t¹, t², t³ on the shafts of the upper distributor wheel, the upper elevator pulley, the upper depositor pulley and the rotatable 40 clearing brush, respectively, as shown in Figs. 1, 2, 3 and 4.

We claim as our invention:

1. A mechanism for feeding string beans and similar articles comprising a supply 45 hopper having an outlet at its front end, an elevator having an endless belt which moves in an upwardly and forwardly inclined position past said outlet and provided with buckets which lift the material from said 50 hopper, and a distributing device having brushes which move downwardly past the buckets on the operative part of said elevator belt, the brushes engaging with the upper operative part of the elevator belt and 55 the respective buckets being arranged close to the same while the brushes engaging with the lower operative part of the elevator and the respective buckets are arranged less closely to the same.

60 2. A mechanism for feeding string beans and similar articles comprising a supply hopper having an outlet at its front end, an elevator having an endless belt which moves in an upwardly and forwardly inclined position past said outlet and provided with

buckets which lift the material from said hopper, and a distributing device having brushes which move downwardly past the buckets on the operative part of said elevator belt, an inclined belt carrying said 70 brushes, and wheels around which pass the upper and lower parts of said belt; the opposing operative parts of said elevator belt and distributing belt converging upwardly.

3. A mechanism for feeding string beans 75 and similar articles comprising a supply hopper having an outlet at its front end, a belt having its receiving part inclined forwardly and upwardly past said outlet and provided with a plurality of buckets, an independent movable depositing device which receives at its upper turn the material from the buckets at the upper turn of the elevator belt, and a plurality of movable pockets 80 which receive the articles successively from the lower turn of said depositing belt.

4. A mechanism for feeding string beans or the like, comprising a supply hopper having an outlet at its front side, an elevating belt having its receiving part inclined forwardly and upwardly past said outlet and provided with a plurality of elevating buckets, an independent movable depositing device which comprises a depositing belt having an inclined part which descends adjacent 95 to the idle part of said feeding belt and which has a plurality of depositing buckets receiving the material from said elevating belt adjacent to the upper turns of said belts, each of said depositing buckets having 100 a concave form in a plane parallel with the direction of travel of the bucket, walls closing opposite ends of the buckets, and a plurality of pockets movable past the lower turn of the depositing belt and receiving the material 105 successively from the latter.

5. A mechanism for feeding string beans and similar articles comprising a supply hopper having an outlet at its front end, an elevator having a belt movable with its operative part upwardly past said outlet and provided with a plurality of buckets, an endless depositing belt movable with its operative part downwardly at an angle from the upper end of said elevator to said pockets and provided on its face with a plurality 110 of buckets which receive the material from said elevating belt adjacent to the upper turn of said belt, upper and lower pulleys around which the upper and lower turns of the depositing belt pass, and a plurality of pockets which move past the lower turn of said depositing belt and which receive the material successively from the latter at said lower turn.

6. A mechanism for feeding string beans and similar articles comprising, a bucket carrying depositing belt which receives the material and which has a downwardly moving operative part, a plurality of pockets 120 125 130

movable past the lower turn of the depositing belt and receiving the articles successively therefrom, and a deflector for directing the material from the lower end of the 5 depositing belt to said movable pockets.

7. A mechanism for feeding string beans and similar articles comprising a supply hopper having an outlet at its front end, an elevator having a belt movable with its 10 operative part upwardly past said outlet and provided with a plurality of buckets, a plurality of movable pockets, a depositing device which receives the material from the buckets at the upper end of the elevator belt 15 and which deposits the material in said pockets and yielding shields engaging with the opposite ends of said pockets.

8. A mechanism for feeding string beans and similar articles comprising a supply 20 hopper having an outlet at its front end, an elevator having a belt movable with its operative part upwardly past said outlet and provided with a plurality of buckets, a plurality of movable pockets, a depositing device 25 which receives the material from the buckets at the upper end of the elevator belt and which deposits the material in said pockets, and shields for preventing escape 30 of the material from said pockets consisting of longitudinal brushes engaging their bristles with opposite ends of said pockets.

9. A mechanism for feeding string beans and similar articles comprising a supply hopper having an outlet at its front end, an 35 elevator having a belt movable with its operative part upwardly past said outlet and provided with a plurality of buckets, a plurality of movable pockets, a depositing device 40 which receives the material from the buckets at the upper end of the elevator belt

and which deposits the material in said pockets, and a brush arranged to engage with the upper ends of said pockets.

10. A mechanism for feeding string beans and similar articles comprising a supply 45 hopper having an outlet at its front end, an elevator having a belt movable with its operative part upwardly past said outlet and provided with a plurality of buckets, a plurality of movable pockets, a depositing device 50 which receives the material from the buckets at the upper end of the elevator belt and which deposits the material in said pockets, and a rotatable brush arranged transversely above the pockets and having 55 spiral bristles.

11. A mechanism for feeding string beans and similar articles comprising a supply hopper having an outlet at its front end, an elevator having a belt movable with its 60 operative part upwardly past said outlet and provided with a plurality of buckets, a plurality of movable pockets, a depositing device which receives the material from the buckets at the upper end of the elevator belt 65 and which deposits the material in said pockets, a stationary brush arranged transversely above the pockets in front of the lower part of said depositing belt, and a rotatable brush arranged transversely above 70 said pockets and having spirally arranged bristles.

Witness our hands this 16th day of June, 1908.
